UNITED STATES PATENT OFFICE

115,017

DESIGN FOR A CAKE OF SOAP

Edwin V. Babbitt, Marion, Mass.

Application September 16, 1938, Serial No. 79,934

Term of patent 14 years

To all whom it may concern:

Be it known that I, Edwin V. Babbitt, a citizen of the United States, residing in Marion, in the county of Plymouth and State of Massachusetts, have invented a new, original, and ornamental Design for a Cake of Soap, of which the following is a specification, reference being had to the accompanying drawing, forming part thereof.

I claim:

The ornamental design for a cake of soap, as shown.

EDWIN V. BABBITT.
